HOSE REEL

Frank P. Zierden, Milwaukee, Wis.

Application October 12, 1954, Serial No. 32,649

Term of patent 14 years

(Cl. D91—1)

*Fig. 1Fig. 2*Fig. 1 is a front perspective view of a hose reel embodying my new design; and

Fig. 2 is a side elevational view thereof, all sides of the hose reel being identical.

I claim:

The ornamental design for a hose reel, as shown and described.
